UNITED STATES PATENT OFFICE.

ANDREW HALLNER, OF ARBOGA, CALIFORNIA.

VEHICLE-SPRING.

1,344,204.

Specification of Letters Patent. Patented June 22, 1920.

Application filed April 7, 1919. Serial No. 288,109.

To all whom it may concern:

Be it known that I, ANDREW HALLNER, a citizen of the United States, residing at Arboga, in the county of Yuba and State of California, have invented certain new and useful Improvements in Vehicle-Springs; and I do declare the following to be a full, clear, and exact description of the invention, such as will enable others skilled in the art 10 to which it appertains to make and use the same.

My present application is along the same line of invention as my prior Patents, 1208956 of December 12, 1916, and 1252690 of January 8, 1918.

One object of the invention is to provide a spring device in which a number of levers are pivotally movable around a common fulcrum point against spring action, without 20 the necessity of employing a positive fulcrum for the levers.

A further object is to provide a spring particularly well adapted for vehicles, by permitting slight endwise sliding of the 25 levers against spring tension and to thereby prevent the transfer of side shocks from the vehicle running gear to the body thereof.

With the foregoing in view, the invention resides in the novel features of construction, 30 and unique combinations of parts herein-after fully described and claimed, the descriptive matter being supplemented by the accompanying drawings.

Figure 1 is a side elevation of one form of 35 spring device constructed in accordance with the present invention.

Fig. 2 is a horizontal section on the plane indicated by the line 2—2 of Fig. 1.

Fig. 3 is a disassembled view of the several 40 levers employed in the spring device of Figs. 1 and 2.

Fig. 4 is a side elevation of a different 45 form of spring device.

Fig. 5 is an upper edge view of the device shown in Fig. 4.

Fig. 6 is a disassembled perspective view 50 of the four levers employed in the device shown in Figs. 4 and 5.

Figs. 7 and 8 are perspective views of still 55 further forms of the invention.

In the form of the invention shown on Sheet 1 of the drawings the numerals 1 and 2 designate a plurality of levers which overlap each other. All of the levers 2 diverge 55 upwardly from a common fulcrum point 3,

while the levers 1 similarly diverge downwardly from said point. At least four levers are required, two diverging upwardly and two diverging downwardly from the point 3, but in the present application I have illustrated 60 eight levers. All of the levers 1 and 2 are of the same construction, the inner overlapping ends of said levers being preferably of disk-shape as seen at 4 and provided with openings 5 above and below their 65 centers, the ends of said openings forming abutments 6 preferably shaped in the manner shown. The several disks 4 are tied together by a central rivet or the like passing loosely through slots 7 therein, but this 70 rivet is in no sense a positive fulcrum for the levers and may well be eliminated if other means are provided for preventing lateral separation of said levers. Coiled springs 8 in the openings 5 and bearing 75 against the opposed abutments 6, control the relative movement of the levers and the location of these springs is such that no positive fulcrum is necessary.

When the ends of the levers are attached, 80 for instance to brackets 9 on a vehicle running gear and to a bolster or the like 10 on the vehicle body 11, all shocks will be absorbed, both vertical and horizontal. When the running gear and the vehicle body move 85 toward or away from each other, the levers will swing around the fulcrum point 3 against the tension of the springs 8 and at the same time will relatively slide to a slight extent against the tension of said springs. 90 Also, when side thrusts are exerted on the running gear by travel of the vehicle over a rough roadway, the lower levers 1 do not directly impart their endwise thrust to the upper levers 2, but the shock is absorbed by 95 the springs 8, it thus being seen that side thrusts of the running gear will not be directly imparted to the vehicle body, thus making riding exceptionally comfortable.

In Figs. 4, 5 and 6, a different form of 100 construction is shown. In this type of spring device, two inner levers 1^a are interposed between two outer levers 2^a, said levers 1^a being by preference spaced apart by a suitably shaped plate 12. All of the levers 105 1^a and 2^a include a body portion 13 from which the ends of the levers extend oppositely as shown, one end 14 of each lever preferably extending in a horizontal direction 110 from substantially the center of the

body 13, while the other end 15 extends from the upper edge of said body and curves downwardly. The several levers 1^a and 2^a are tied together by a bolt or the like 3^a located at a common fulcrum point about which the two levers move, but here again, as in the form of the device above described, the bolt 3^a is merely a tie to hold the several levers together and is not a positive fulcrum. 10 the relative movement of the levers being controlled entirely by the coiled springs 8^a bearing against abutments 6^a formed either by notching the levers as seen at 5^a in Fig. 6, or by forming openings 5^b therethrough. In 15 the present application, I have shown both ways of forming the abutments, but either one or the other may be employed. The levers 1^a and 2^a may all be provided with slots to receive the bolt 3^a, but it is sufficient if slots 20 be formed only in one set of levers as shown at 7^a while ordinary bolt holes such as 7^b are formed in the others.

In the form of the device just described, any pivotal movement of the levers around 25 their common fulcrum point will act equally against both springs 8^a and any endwise sliding of said levers will be cushioned by these springs.

Figs. 7 and 8 illustrate levers 1^c and 2^c 30 crossing each other between their ends and provided with openings 5^c whose end walls form abutments 6^c. The openings 5^c receive coiled springs 8^c for cushioning all movement of the levers as they slide with 35 respect to each other or pivot about the common fulcrum point indicated at 3^c. In this form of the invention, the connections which may be used for connecting the ends of the levers to the running gear and body, 40 may be relied upon to tie said levers together and for this reason I have shown no tie or bolt or the like; and it will be understood that the ties 3 and 3^a above described might well be eliminated if other adequate 45 means are employed to prevent excessive spreading of the several levers at their overlapped portions.

It will be observed that Fig. 7 discloses 50 four of the springs 8^c and a proportionately increased number of abutments 6^c, whereas Fig. 8 illustrates only two springs as in the forms of the device previously described; and it may be explained that any number of springs may be used in any of the several 55 forms of the device, but at least two are necessary, disposed on opposite sides of the common fulcrum point of the levers. Otherwise, a positive fulcrum is necessary and the present invention is intended to render 60 the use of such a fulcrum unnecessary, this being of great advantage since the continual rocking of the levers upon a positive fulcrum, causes excessive wear of both levers and fulcrum. Such wear, however, is of

course eliminated when no positive fulcrum 65 is used.

All forms of the invention are comparatively simple and inexpensive, yet will be highly efficient and in every way desirable, serving not only to absorb the usual shocks, 70 but the recoil. Since probably the best results may be obtained from the detail disclosed they may well be followed, but within the scope of the invention as claimed numerous minor changes may well be made. 75

I claim:

1. A spring device of the class described comprising overlapped levers extending oppositely and slidable longitudinally with respect to each other, said levers also having relative pivotal movement around a common fulcrum point, and at least two coiled springs at opposite sides of said fulcrum point for controlling the sliding and pivotal movement of the levers, said levers 85 having pairs of opposed abutments contacting with the ends of said springs.

2. A spring device of the class described comprising at least four overlapped levers, two diverging upwardly and the other two 90 diverging downwardly from a common fulcrum point around which they are pivotally movable, and spring means for controlling the movement of said levers.

3. A spring device of the class described 95 comprising at least four overlapped levers, two diverging upwardly and the other two diverging downwardly from a common fulcrum point around which they are pivotally movable, said levers being longitudinally 100 slidable with respect to each other, and spring means for controlling both the pivotal and sliding movement of said levers.

4. A spring device of the class described comprising at least four overlapped levers, 105 two diverging upwardly and the other two diverging downwardly from a common fulcrum point around which they are movable, and at least two coiled springs disposed at opposite sides of said fulcrum point to control the movement of the levers, said levers having opposed abutments contacting with the ends of said springs.

5. A spring device of the class described comprising at least four overlapped levers 115 slidable relatively, two of said levers diverging upwardly and the other two diverging downwardly from a common fulcrum point around which said levers are movable, and at least two coiled springs disposed at opposite sides of said fulcrum point for controlling the pivotal and sliding movement of the levers, said levers having spaced abutments contacting with the ends of said springs. 120

In testimony whereof I have hereunto set my hand.

ANDREW HALLNER
